UNITED STATES PATENT OFFICE.

HERMAN J. SCHULTZ, OF CHICAGO, ILLINOIS, ASSIGNOR TO W. E. HALL PRINTING CO., OF CHICAGO, ILLINOIS, A CORPORATION OF ILLINOIS.

PRINTING PRESS.

Application filed December 18, 1922. Serial No. 607,494.

This invention relates to improvements in printing presses and refers more particularly to an automatically operated and self stopping machine, and one in which the feed is regulated and the impression released when the feed is improper.

Among the salient objects of the invention are to provide a mechanism in which rolled out stock is fed in single sheets separated by a suction mechanism and advanced into the press by push rubbers and feed rolls; to provide a press in which an automatic trip functioned by the position of the front edge of the stock rather than the thickness of the stock operates to stop the press in case the stock is improperly fed; to provide a press having an automatic trip for separating the impression rolls in case the sheets are fouled or improperly fed thereto, and in general to provide a mechanism of the character referred to.

Fig. 1 is a side elevation of the press.

Fig. 2 is a side elevational view of a portion of the press disclosing in more detail the suction mechanism and drive for the feed.

Fig. 3 is a plan view of the mechanism shown in Fig. 2.

Fig. 4 is a detail view taken along the line 4—4 in Fig. 3.

Fig. 5 is an enlarged detail of the single sheet suction mechanism.

Fig. 6 is a perspective detail of the push rubbers.

Fig. 7 is a detail view partly in section of the feed control mechanism.

Fig. 8 is an enlarged detail of the feed actuating mechanism.

Fig. 9 is a view taken along the line 9—9 in Fig. 7.

Fig. 10 is a view taken along the line 10—10 in Fig. 14.

Fig. 11 is a view showing the detail arrangement of the automatic releasing mechanism for separating the impression rolls.

Fig. 12 is a view taken along the line 12—12 in Fig. 14, looking in the direction of the arrow.

Fig. 13 is a similar showing of the detecting mechanism in operating position.

Fig. 14 is a view partly in section showing further details of the impression roll separating mechanism.

Referring to the drawings, the press con-

sists of a feed table, a suction mechanism by means of which the rolled out stock is separated into individual sheets and the sheets thence fed to the press. Along the front edge of the stock is positioned a load regulating mechanism by means of which the feed of the stock to the suction mechanism is automatically regulated, that is, instead of controlling the feed of the stock by the height of the stock, the position of the front edge controls the automatic feed.

After passing this controlling mechanism, the sheets are directed between the plate and packing rolls where they are printed, and subsequently to a collecting means where they are arranged and stacked. To prevent the crushing of the printing plates due to the fouling of the sheets between the impression rolls, or in the case of an improperly fed sheet, there is cooperating with the packing roll, an automatic mechanism for separating the packing roll from the plate roll so that the rolls lose their impression upon each other.

The sheets to be fed to the press are rolled out in a manner shown in Figs. 4 and 5 and arranged in position on the feed table 1. Beneath the feed table are traveling tapes 2 operating over feed rolls 3, the rear one being eliminated from Fig. 4 due to the breaking away of the feed table. As the sheets progress, they are contacted by a suction head 4 connected to the suction air pipe 5. The suction head reciprocates, operating against a compression spring 6 which abuts against the collar 4^a on the suction head, and on its opposite end against the end of the adjustable holder 7. It will be noted that this holder is adjustably mounted at 8 so as to be set at any desired angle whereby there is assured a positive lift of each individual sheet as it gets into position. The holder 7 is adjustably fixed to the end of the lift arm 9, which is pivoted to the shaft 10 shown in Figs. 3, 4 and 5. This lift arm is actuated by a cam 11 pivoted on the rotatable shaft 12 and operating against the roller 13 bearing in the arm 14 fixedly attached to the shaft 10.

The lift arm is lowered on to the stock at which time due to the suction in the pipe, a single sheet is drawn on to the end of the suction head. The lift arm is then raised by the cam 11 and the separating feet are 110

then moved into place beneath the sheet as will hereinafter be explained, and simultaneously with this positioning of the feet beneath the sheet, a clapper mechanism inter-

posed in the suction hose 5 releases the vacuum action and permits the sheet to drop on to the separating feet.

The clapper mechanism shown in Fig. 3, consists of a flat plate or clapper 16 positioned at the end of an arm which is raised and lowered by means of the cam 17 mounted upon the shaft 12 and operating against the roller 18 on the clapper arm. The cam is so set upon the shaft that the clapper functions at the time when the suction head has a sheet in a raised position, and the separating feet are in place beneath the sheet. The clapper merely opens a valve in the hose line and releases the vacuum action or suction upon the suction head permitting the sheet to drop on to the separating feet.

Explaining now the functioning of the separating feet, the feet proper are two in number, shown in Figs. 2, 3, 4 and 5. The feet are pivoted at 19 to the hangers 20 which give them their forward and backward movement. In addition to this movement, there is a raising and lowering movement, which is produced by a separate mechanism. In connection with the raising and lowering of the feet, the hangers 20 are fixed to the oscillating shaft 21 shown in Figs. 2, 3, 4 and 5. At one end of this shaft is an arm 22, which is connected to a member 23 having a bifurcated lower extremity shown at 23^a. To this member 23 is pivoted a roller 24 which contacts with a cam 25 mounted upon the rotating shaft 12. This mechanism is best shown in Fig. 2. With the rotation of the shaft, the cam reciprocates the member 23, and oscillates the shaft 21 to move the feet backward or forward against the tension of the springs 26 attached to the rear extremities of the separating feet, and also to the hangers 20.

In order to give the feet the raising and lowering movement, there are the crank arms 27 and 27^a and supporting right arms 28 pivoted to the arms 27^a at 29, and the supporting arms 28 to the separating feet by slidably pivot pins 30 functioning in the slots 31. The details of this mechanism are best shown in Figs. 4 and 5. The crank arms 27^a are fixedly mounted on the oscillating shaft 32, while fixed to the same shaft is the arm 27. At the free end of the arm 27 is a cam roller 33 contacted by the cam 34 also fixed to the rotating shaft 12. As the cam 34 rotates with the shaft, it rocks the crank arm 27, thereby raising and lowering the separating feet while the previous mechanism explained in connection with the hangers 20 give the feet their forward and backward movement. Thus the feet are actuated to be lowered beneath the paper

sheet as it is raised by the suction head and hold the remaining stock in position while the single separated sheet is moved forward by the rubber pushers 35.

The rubber pushers as shown in detail in Fig. 6, consists of rollers 35 bearing in the supports 36 which are positioned at the end of arms 37 pivoted at 38 to the horizontal stub shafts 39. A coil spring 40 on the shafts 39 give the arms 37 a constant downward tension against the paper stock, the travel of the arms being limited by the stops 41. These stops eliminate undue friction between the roller and paper. Knives 42 are positioned against the rubber pushers 35 so that they are rotatable only in a reverse direction, that is, they rotate when they are being oscillated in an opposed direction to the travel of the paper sheets.

The stub shafts 39 are carried by the arms 43 fixed to the shaft 44 oscillated by arms 45 and 46 connected by the member 47 to the outside driving mechanism shown in Fig. 3. The pushers are thus oscillated backward to engage the front edge of the paper sheet, and as the pivoted shaft again moves the pushers 35 forward, they are prevented from rotation by the knives 42, and frictionally engage the surface of the sheet, drawing the sheet with them. The sheet is taken up by drop rollers 48 bearing in the arms 49 which are pivoted on the oscillating shaft 50, shown in Fig. 3. It is unnecessary to explain the details of the operation of the drop rollers, as they merely assist in feeding the sheets on to the traveling tapes 51 where they are carried along to the impression rolls.

Immediately in front of the paper stock as it is advanced to the feed is a load regulating finger 52 shown in Figs. 7 and 9. This load regulating finger is pivoted at 53, and is held in position against the front of the oncoming paper sheet by a weight 54 adjustably set on the rod 55. Central of the load regulating finger is a notch 52^a into which fits the stop 56 mounted at one end of the crank arm 57. This crank arm is pivoted to the feed control shaft 58, and has at its opposite end a cam roller 59 contacting the cam 60 mounted on the shaft 87. The cam roller is held in contact with the cam by means of a spring 61.

When the stock is in a position so as to hold the load regulating finger in a position shown in full lines in Fig. 7, the stop 56 will contact the notch 52^a and prevent the crank arm from oscillating when the low side of the cam 60 has rotated to contact with the cam roller 59. If however, the front end of the stock recedes so as to permit the weight 54 to move the finger on its pivot so as to assume a position shown in dotted lines in Fig. 7, it will then be in a position where the notch 52^a will not support the stop, and

consequently with the rotation of the cam the crank arm will assume a position shown in the dotted lines in Fig. 7 due to the action of the spring 61 which imposes a constant rotative tension upon the hook member 62 rigidly fixed to the feed control shaft 58.

At one end of the feed control shaft is fixedly mounted an arm 63 shown in Figs. 2 and 8. This arm contacts one end of a pivoted lock 64 which has engagement at its opposite end with a notched rocker arm 65. This rocker arm is loosely mounted upon the feed roller shaft 66 which also carries a ratchet 67 which is fixedly attached thereto.

A dog 68 is pivoted to the rocker arm 65. A constant downward rotative tension is kept upon the arm by means of a spring 69. The rocker arm is connected by means of a connecting rod 70 to a pin 71 offset from the center of the gear wheel 72 so that the gear wheel in its rotation will rock the rocker arm upon its pivot due to the reciprocating movement of the connecting rod 70.

Normally the reciprocatory movement of the connecting rod, due to the rotation of the gear, is taken up by the slot 73 in the connecting rod.

Thus, it is obvious that as long as the front edge of the stock holds the load regulating finger in position, shown in full lines in Fig. 7, the crank arm 57 is prevented from actuating, but as soon as the stock does not advance to this position sufficiently to hold the load regulating finger so as to support the stop positioned at the end of the crank 57, the crank will be actuated due to the spring tension and will function the arm 63 so that the lock 64 will release the rocker arm. The rocker arm will be rocked by the spring 69, and the dog 68 will engage the ratchet and the ratchet will in turn be drawn by the reciprocation of the connecting rod 70 whereby the feed shaft 66 will be rotated and the load advanced.

After passing the load regulating finger, the sheets are engaged by the pushers as explained, and are contacted by the drop rollers 48 which are raised and lowered by cams 74 contacting with the rollers 75 rotatably positioned on the arms 76, which are in turn fixed to the oscillating shaft 50.

Tension is kept upon the arms 49 which carry the rollers by springs 77. These rolls advance the sheets on to the tapes 51 as explained. The drive to the gear 72 is shown in Fig. 2, power being transmitted from the press through the chain 78 to the sprocket 79 mounted on the shaft 80, thence through a gear 81 carried upon the same shaft. This gear meshes with the gear 82 mounted on the shaft 83 which is in turn meshed with the gears 84 and the latter meshed with the gear 85 mounted upon the feed roll shaft 86 over which the feeding tapes 51 pass. The gear

85 is meshed with the larger gear 72. The gear 72 is mounted upon a rotating shaft 87 upon the opposite end of which is positioned a bevel gear 88 meshed with a similar bevel gear 89 positioned at right angles thereto, and carried by the drive shaft 20. This drive shaft through the bevel gears 91 and 92 drives the rotating shaft 12 which functions the separating feet and suction mechanism explained in connection with Figs. 2, 3 and 4. The sheets after passing on to the tapes 51 are carried on the printing and impression rolls which consist of a plate cylinder 93 keyed to shaft 94 and a packing cylinder 95 keyed to a shaft 96. These cylinders are driven by meshing gears 97 and 98 mounted upon the shafts 94 and 96, respectively. The cylinder-bearing boxes 99 which support both ends of the shaft 96, shown in Fig. 10, are slidably mounted in the frame 100. These cylinder-bearing boxes 99 are connected by eccentric connecting rods 101 to the eccentrics 102 keyed upon the impression throw-off shaft 103. To the gear 98 is pivoted a reciprocating crank rack 104 which meshes with the gear 105 positioned in the gear case 106 fixedly mounted on the impression throw-off shaft 103. To the gear is fixed a circular plate 107 having a dog 108 pivotally mounted thereon at 109. Near the end of the dog is positioned a transverse pin 110 which is engaged by the cam 111^a of the cam plate 111, which is loosely mounted on the shaft 103 and prevents the dog from dropping into the notch 111^b of the notched plate 111^c. The cam portion 111^a of the cam plate 111 communicates with a member 112 mounted upon the shaft 113 shown in Figs. 11, 12 and 13. This member and shaft are oscillated by the pivoted connecting rod 114 which has communication both with the member 112 and with the cam portion of the cam plate 111. This oscillation takes place against the tension of the spring 115 shown in Fig. 11. Upon shaft 113 are also adjustably mounted arms 116 which carry depending detectors 117. These detectors normally contact the surface of the paper sheets as shown in Fig. 13, but in case a sheet is improperly fed to the impression rolls, the hole 118 shown in Fig. 12 is uncovered, and the detectors drop into the holes, thus preventing the oscillation of the shaft 113 and permitting the transverse pin 110 to drop off of the notched portion of the cam 111^a, which allows the dog 108 to drop into the notch 111^b of the notched plate 111^c.

Normally actuating, when the sheets are properly being fed to the impression rolls, the circular plate 107 will be oscillated with the gear 105 backward and forward through a semi-circular rotation. During this oscillation the pin 110 will remain supported by the notched cam plate and will be prevented

from dropping into the notch 111^a and thereby rotating the impression throw-off shaft. When however, the detector or depending rods 117, or either of them, drop into holes 118, the oscillation of the member 112 and the consequential oscillation of the shaft 113 will be prevented and the pin 110 will drop off of the notched portion of the cam plate into the notch 111^b where it will 10 rotate the impression throw-off shaft, and through the eccentric as explained, will move the slideable cylinder bearing boxes along the ways in the frames separating the impression rolls and preventing the printing of the sheets and crushing or breaking the plates on the plate roll due to fouling 15 of the sheets in the press.

In Fig. 11, the rolls are shown in full lines in contacting position and in dotted lines 20 when they are moved apart. The second or the separated position shown in dotted lines, has however, been somewhat exaggerated for clearness, for in operation although the impression rolls are separated, the driving gears do not become separated to an extent that they lose their driving relation.

In addition to the separating of the impression rolls, the functioning of the impression throw-off shaft also actuates an 30 electric circuit breaker not shown, to stop the press.

After passing through the impression rolls the printed sheets are collected and stacked 35 in a jogger mechanism which is well known in the art, and no part of this invention.

The explanation of the drive of the impression rolls is unnecessary and superfluous to the understanding of the invention. Also, the inking mechanism has purposely 40 been entirely omitted to shorten the explana-

tion. The inking mechanism is similar to that used on a press of this type.

I claim as my invention:

1. In a printing press, the combination with means for feeding rolled out stock in single sheets to the press, comprising suction means adapted to select the individual sheets, means for supporting and advancing the single sheets to printing and impression rolls of the press, and means functioned by the position of the forward edge of the rolled out stock for automatically controlling the feed of rolled out stock to the press. 45

2. In a printing press, the combination with means for feeding stock to the press, comprising suction means adapted to select the individual sheets, of a feed control means automatically functioned by the advancing and retarding of the front edge of the stock to actuate the feeding means to feed 50 sheets to printing and impression rolls of the press mounted in slideable bearings in the press frame, and means for directing the sheets thereto, automatic tripping means functioning through an eccentric connection 55 to separate the rolls with improper feeding of the sheets.

3. In a printing press, the combination with means for feeding stock to the press, comprising suction means adapted to select the individual sheets, of a feed control means automatically functioned by the advancing and retarding of the front edge 70 of the stock to actuate the feeding means to feed sheets to printing and impression rolls 75 of the press, and means for directing the sheets thereto, automatic tripping means functioning to separate the rolls with improper feeding of the sheets.

HERMAN J. SCHULTZ.
